UNITED STATES PATENT OFFICE.

FRANK FELIX HOLLAND, OF CORPUS CHRISTI, TEXAS.

HEMSTITCHING ATTACHMENT FOR SEWING MACHINES.

Application filed March 22, 1922. Serial No. 545,775.

To all whom it may concern:

Be it known that I, FRANK FELIX HOLLAND, a citizen of the United States, residing at Corpus Christi, in the county of Nueces and State of Texas, have invented new and useful Improvements in Hemstitching Attachments for Sewing Machines, of which the following is a specification.

This invention relates to hemstitching attachments for sewing machines.

The object is to provide a simple, light device capable of being readily attached to the presser foot of any sewing machine, and of being adjusted thereon to bring certain coacting parts into proper relation to the machine needle, said parts consisting of movable arms, one or more of which may be brought into operative position for causing a greater or lesser separation of two pieces of goods, or of the folds of a hem, to produce hemstitching of different widths, the said arms being also capable of swinging entirely out of action to permit of the device being used in picoting.

Another object is to provide such an attachment which, when applied to the presser foot of a machine, extends to the rear of the same and tends to keep all weight directly beneath the presser foot and to prevent the attachment from working off, the layers of goods passing smoothly over and through the device, between a separating bar of even thickness and the main body of the attachment, in perfect alinement and uniform spaced relation, to produce a perfect and regular stitch.

A full and complete understanding of the invention may be obtained from a consideration of the following detailed description taken in connection with the accompanying drawing forming a part of this specification, it being understood that while the drawing shows a practical form of the invention, the latter is not to be confined to strict conformity therewith, but may be changed or modified, so long as such changes or modifications mark no material departure from the salient features thereof as specifically pointed out in the appended claims.

In the drawing, in which similar reference characters designate corresponding parts throughout the several figures:

Figure 1 is a sectional view taken transversely through the bed plate of a sewing machine, showing the cloth feeder, presser

foot and needle bar in elevation, the improved attachment being applied to the presser foot.

Figure 2 is a detail perspective view of the attachment removed from the machine, the presser foot being indicated in dotted lines.

Figure 3 is an enlarged detail sectional view of the device, taken on the line 3—3 of Figure 2.

Figure 4 is a similar view, taken on the line 4—4 of Figure 2.

In the drawing, there is shown the bed plate 1 of a sewing machine which is indicative of the structure of a number of well known makes of sewing machines on the market. The bed plate is suitably supported over the usual mechanism of the machine, of which only the cloth feeder 2 is shown including the actuating bar 3 and crank motion 4 for the same. In superposed relation to the cloth feeder, a presser foot 5, of ordinary construction, is employed, the same being carried by the bar 6 mounted for clamping action in the head 7 of the machine arm located above and in spaced relation to the bed plate 1. The needle bar 8 projects in the usual manner from the lower end of the head 7, and is suitably mounted therein to have the necessary movement for imparting reciprocatory motion to the needle 9, all of which forms no part of the present invention.

The improved hemstitching attachment comprises a base plate 10 formed of a strip of thin metal, preferably steel, and considerably longer than wide, one end of the strip being bent under as at 11 to lie flat against the lower face of what constitutes the forward end of the base plate, and the opposite or rear end being bent upwardly 95 to form a narrow flange 12 extending entirely across the same. Adjacent to its front end, the base plate is further provided with upstanding side walls 13, formed by providing on the base plate integral outstanding wings which are turned upwardly in perpendicular relation to the base plate and extend rearwardly somewhat less than half the length of said base plate. One of the side walls 13, or what may be termed the left hand wall as viewed by the operator of the machine, is provided with a set screw 14 passing through the same and adapted to bind against some portion of the forwardly extending, bifurcated portion of the presser 110

foot 5, the said set screw serving to adjust the base plate 10 forwardly or rearwardly to bring certain parts to be described in proper relation with the machine needle 9.

5 Threaded into the base plate at the longitudinal center line thereof, and adjacent to the upstanding flange 12 formed at the rear end of the same, is a binding screw 15 traversing a slot 16 provided longitudinally in 10 a transverse rear bar 17 forming one branch of an adjustable U-shaped bracket 18, the said rear bar having its rear edge in contact with the flange 12 throughout the length of the latter, so as to prevent any lateral 15 play of the bracket with respect to the base plate.

The bracket 18 comprises, in addition to the rear bar 17, a front, cloth-separating bar 19, arranged parallel to the rear bar and joined 20 to the same by a connecting bar 20, which is bent intermediate its length to bring the said front bar 19 in a lower plane than the rear bar 17, and slightly below the upper surface of the base plate, the rear or inner edge of 25 the separating bar 19 being in spaced relation to the front, rounded edge of the base plate, to provide a space 21 for the free passage of the upper layer of cloth in a manner to be explained.

30 At the intersection of the front bar 19 and the connecting bar 20 of the adjustable bracket 18, a plurality of swinging arms 22 are pivotally mounted on a bolt or rivet 23 secured to the bracket and passing through 35 suitable apertures in the ends of said arms in a manner to permit one or more of the latter to be swung around in alinement with the separating bar 19, or to be moved into an out-of-the-way position, as illustrated in 40 Figure 2 of the drawing. The separating bar 19 is provided with a needle opening 24 for the passage of the needle 9 and connecting with a slot 24^a extending to the rear edge of the bar for the escape of the thread in a 45 well known manner, as the goods are fed rearwardly by the serrated cloth feeder 2. The swinging arms 22 are likewise provided with needle openings 25 to be brought into alinement with the aforesaid opening 24, and likewise provided with communicating slots 25^a to be alined with the slot 24^a, when 50 the arms are in use, for a like purpose.

The base plate carrying the adjustable bracket 18 may be positioned upon the 55 presser foot of the machine in a forward or backward direction to bring the needle opening or openings in proper position with relation to the needle 9, by means of the set screw 14, which may be brought to bear at 60 the proper point along the forwardly extending, bifurcated portion of said foot. In like manner the opening 24 of the cloth-separating bar 19 may be adjusted laterally by means of the set screw 15, to properly 65 position the same for the passage of the

needle and, of course, when the arms 22 are swung into alined relation to the bar 19, the perforations 25 will register properly.

In using the device for narrow hemstitching or for picotting, the front cloth separating bar alone is utilized and when wider hemstitching is being done, one or more of the arms 22 may be swung into alinement with the bar as may be found necessary, it being understood that while only two of the 75 said arms are illustrated in the drawing, more may be supplied with the attachment and used, when extra wide hemstitching is desired.

The lower layer or strip *a* of cloth or 80 fabric is placed upon the bed plate 1 in the usual manner, the serrated upper surface of the feeder 2 coming into contact with the same. The upper layer or strip *b* is placed over the bar 19 together with the interposed arms 22, if the latter are to be used, and the strip *b* is then passed downwardly through the slot or space 21, and beneath the presser foot 5, to be held firmly against the lower strip or layer, when the said foot 90 is depressed in the usual manner, the feeder then acting to feed both strips in a rearward direction when the machine is operated. The rounded forward edge of the base plate 95 10 serves to guide the upper layer beneath the presser without damaging the same, and as the needle passes up and down through the more or less spaced layers or material caused by the interposed bar and arms, the stitches will free themselves from the latter 100 through the respective slots 24^a and 25^a, as will be seen.

From the foregoing it will be seen that a simple, cheaply manufactured and efficient 105 hemstitching attachment for sewing machines has been provided, which may be easily and quickly applied to the presser foot of an ordinary machine in a manner to avoid obstructing the view of the operator, and that the same may be readily adjusted forwardly or backwardly or in a transverse direction to position the parts properly 110 with relation to the machine needle, and further that by simply swinging one or more of the arms into position, hemstitching 115 of different widths may be done.

What is claimed is:—

1. An attachment for a sewing machine having a presser foot and a needle cooperating therewith, comprising a base plate having means for attachment to the presser foot of the machine, with a portion of the plate extending to the rear of the presser foot, said base plate being forwardly and rearwardly adjustable, an integral upturned flange at the rear edge of the base plate, a substantially U-shaped bracket having one branch secured to and adjustable transversely of the base plate in abutting relation to said flange, and the other branch arranged 130

substantially parallel and in spaced relation to the front end of said plate and having a needle opening, the adjustment of said bracket serving to aline the needle opening 5 with the machine needle.

2. An attachment for a sewing machine having a presser foot, comprising a base plate having means for attachment to the presser foot of the machine, said base plate 10 extending to the rear of the presser foot and adjustable forwardly and rearwardly on the same, a bracket mounted on the base plate and provided with means for adjustment laterally of the base plate, said bracket having a front transverse bar which is arranged in spaced relation to the front 15 end of the base plate, said bar having a needle opening, and a plurality of arms pivotally mounted on said bar and having similar 20 needle openings adapted to be swung into and out of registering relation with the needle opening in the front bar.

3. An attachment for a sewing machine having a presser foot, comprising an elongated base plate having upturned walls at 25

its forward end adapted to straddle the presser foot of the machine, a set screw passing through one of the walls and adapted to bear against the side of the foot to hold the plate in position and to permit 30 of forward and rearward adjustment of the same, a transverse flange formed at the rear end of the plate, a bracket having spaced substantially parallel front and rear bars joined at one end of each by a connecting bar, the rear bar having a longitudinal slot and adapted to abut against the rear flange of the base plate, a set screw traversing the slot and entering the base 35 plate to permit of lateral adjustment of the bracket, the front bar being provided with a needle opening having a thread releasing slot, and a plurality of arms pivotally mounted on the front bar and having similar 40 needle openings and slots and adapted to be swung into and out of register with the opening in the front bar.

In testimony, that I claim the foregoing as my own, I have hereto affixed my signature.

FRANK FELIX HOLLAND.
